MULTIPLE CONTACT ROTARY AND
LINEAL SWITCH

Robert M. Dyksterhouse, Charlevoix, Mich., assignor, by
mesne assignments, to Circuit Controls Corporation,
Petoskey, Mich., a corporation of Michigan
Filed Jan. 25, 1962, Ser. No. 168,680
6 Claims. (Cl. 200—4)

The present invention has reference to a new and useful electrical switch and more particularly to a rotating actuation detenting switch having provisions for axial movement therethrough without upsetting the switch actuation. More particularly the switch of the present invention is directed to a cage housing for selected radially positioned contacting posts, adjacent of said posts being selectively bridged by an interposed roller element which is spring biased into radial detenting relationship between adjacent selected of said posts and also in detenting points having no such contacting posts. The shaft rotating the positioning roller is keyed to the actuator rotor carrying the roller element and the shaft selectively causes rotation of the rotor. The shaft is also axially movable in respect to the actuator without disturbing the switch function. The switch is also unique in providing accommodation for Bowden wire connection to apparatus in operative association therewith while providing unique shaft attachment and movement stop limit provisions.

In heater structures for automobiles, trucks, and the like, the electrical equipment, for example "high," "low" and "off" blower settings must be selectively actuated in a detenting manner and must be secure against vibration and shock disengagement in any selected position. In addition, associated equipment of a mechanical nature, for example, air ducting, vanes and the like, require concurrent actuation from a single and common control station or knob. The present invention admits of structure to allow such common control in a single knob or lever capable of simultaneous push-pull control over mechanical actuation and rotational control over electrical circuits with adequate movement stop limit provisions in the switch structure against rotational and lineal overrun.

Accordingly the principal object of the present invention is to provide a switch of rotating and detenting selective type combined with structural provisions to allow axial movement through the switch case without interfering with the setting or selection of electrical contacting relationship.

Another object is to provide the switch as indicated in the principal object and including provisions in the switch structure for accommodating the mounting of mechanical components thereto.

In addition, an object is to provide unique and compact mounting means and stop means in the lineal actuation provisions of the switch so as to assure smooth independent or simultaneous rotational and axial movement and without damage to circuits or to mechanical movement as desired.

Other objects including economy of construction, excellent contacting characteristics, and compact single knob adaptability to dash panel mounting for automotive usage will be increasingly apparent to those skilled in the art as the description proceeds.

In the drawing:

FIGURE 1 is a perspective view of the externals of the switch of the present invention and indicating its mechanical integration with a single control knob indicating an attached Bowden wire mechanism for lineal and rotational movement.

FIGURE 2 is a side elevation view of the switch of the present invention partially cut away to reveal the

FIGURE 9 is a perspective rear view of the switch case with Bowden wire disconnected and showing socket connectors extending therefrom.

General description

In general, an elongate stepped cylindrical housing is provided in which a contacting rotor is positioned. Axially through the rotor and housing a shaft is provided which is keyed to the rotor but which rotates freely in the case or housing. The shaft is also movable axially of the case or housing without disturbing the positioning of the rotor. The rotor is maintained in fixed position on the case axis by a cover provided axially over the shaft and closing the open end of the housing or case. The rotor carries a resiliently biased contact member radially urged into contact with the cylindrical inner wall of the case or housing. On axes parallel to the axis of the rotor and case are terminal pins or posts in paired adjacent relationship. These pins partially extend into the case cavity so that the contact member is locatable in detenting manner, bridging the terminals to close a selected electrical circuit across selected adjacent pins. Plural pairs of these terminal pins are selectively provided in the case as well as radial detent pockets wherein the contactor is detentably retained against contact with the terminal pins. The stem portion of the case or housing is provided with an integral shaft stop against axial movement of the shaft in one direction. An upset on the shaft engageable with the rotor provides a suitable stop limiting axial movement of the shaft in the other direction. The stem and rotor are made from insulating material cast or otherwise formed to the desired shape.

The shaft is connected to a Bowden wire system for push-pull actuation of mechanical apparatus remotely located and not a part of the present invention. The connection is uniquely accomplished by passing an upset end of the core wire of the Bowden wire system axially through the stem end of the case and through an axial passage defined in the shaft. The core wire thus rests in a transverse passage through the shaft so that the upset end of the core wire once positioned in this manner, cannot be withdrawn when the coil wrapping of the Bowden

wire system is press fitted to its receiving socket in the stem end of the case. On the other hand, before seating the coil winding in close coaxial relationship with the core wire end, the core wire is removed or inserted with ease.

As will be appreciated the terminal pins collaterally serve as mounting locators for tabular socket terminal extensions for simple integration with electrical circuits, particularly in the automotive field.

The resultant structure operates well in service allowing push-pull stop limited axial movement of the control shaft while concurrently permitting selected detenting switch contact motion by rotation of the shaft. Neither lineal nor rotational movement is interrupted while one or the other control movements is imparted to the switch. The 15 electrical contacting is excellent and by use of a resiliently backed roller the tangential rolling line contact as between contacting pins and roller is simple and efficient so that detenting is accomplished with contacting selection. By molding case and rotor of material having good insulating dielectric characteristics the balance of the structure is prepared from rugged conducting materials, many of which are available from stock with simple or no machining required.

Specific description

Referring particularly to the drawing and with first reference to FIGURE 1, a switch 11 in accord with the present invention is illustrated. The switch 11 externally comprises an elongate case or housing 12. The case 12 comprises a stem piece 13 and a barrel portion 14, both preferably formed in an integral manner from a dimensionally stable resin material selected for good dielectric or insulating properties. The barrel portion 14 of the case 12 is cylindrical and is stepped to an increased diameter over the stem portion 13. The stem portion 13 is also cylindrical and preferably tapering away from its merger with the barrel portion 14 and is coaxial therewith. A shaft 15, provided with an out-of-round uniform cross sectional configuration, as for example the flat 16, is provided. The shaft 15 passes axially through the barrel portion 14 and the stem portion 13 but as will be seen is prevented from passing wholly through the stem 13. A cover plate 17 closes case 12 at the entry of shaft 15 and the cover plate 17 includes a coaxial boss element 18 having an axial opening therethrough and the boss 18 is provided with an external thread 19. The tubular boss 18 thus provides an elongate bearing against thrust and radial loading of the shaft 15 and mounting means for securing the switch 11 to a desired instrument panel, for example, in a well-known manner. A control knob 20 is keyed to the shaft 15 so that the shaft 15 is rotatable with rotation of the knob 20 and is also reciprocable in accord with lineal push-pull movement of the knob 20. Prong electrical connectors 21, 21a, and 21b (see FIGURES 6 and 9) extend from the shoulder of the barrel 14 in a direction generally paralleling and offset from the axis of case 12. Fasteners 22 secure the cover 17 to the barrel portion 14 of the housing 12. From the stem 13 and coaxially therewith a Bowden wire is provided which comprises a lineally acting wire core element 23 spirally or helically overwound with an encasement 24 and is covered with protective sheath 25. Together these core and winding elements comprise a well-known Bowden wire control which may be flexed as desired while not interrupting the ultimate lineal movement of the core piece 23. As will be later appreciated the core piece 23 moves lineally in accord with the lineal movement of the control knob 20 and the corresponding movement of the shaft 15. At the end of the core piece 23 remote from the stem 13 is a connector 26, integral with or secured to the core piece 23. The connector 26 provides mounting means for integration with collateral equipment, as for example louver opening devices, vane control structure and the like, not shown. The threaded 75

shank or boss 19 provides simple dash mounting means for insertion through an instrument panel (not shown) and accomplishes simple mounting of the switch 11 at the major bearing portion.

From FIGURE 2, cut away to reveal the core wire 23 connection to the shaft 15, and with knob 20 removed, several structural features are best portrayed. The key notch 27 for retention of the knob 20 is revealed near the end of the shaft 15. The opposite end of the shaft 15 is seen to be provided with an axial opening 28 therethrough merging in a transverse relief through opening 29. The stem 13 is also seen to be blocked by the shoulder stop 30 forming a barrier blocking the stem cavity 31 but for the axial opening 32 therethrough. The end of the core piece 23 passes through the opening 32, through the axial opening 29 of the shaft 15, and in upset manner extends into the transverse through opening 29. Hence, the stem 13 is seen to be cored by the stem cavity 31 in coaxial clearance relationship about the shaft 15. On the outboard side of the barrier shoulder 30 the stem 13 continues but is provided with internal shallow grooving 33 providing a cylindrical gripping surface with plural grooving mating with the helix winding of the wrapping or winding 24.

In FIGURE 3, a transverse section through the axis of the barrel portion 14 of the case 12, it is seen that the shaft 15 passes through a rotor piece 34 rotatable in the cylindrical inner recesses 35 of the barrel 14. Actually the rotor 34 is in clearance relationship with the walls of recess 35 except as selectively stopped by radial inward projection or abutments 36 forming stops against rotation overrun of the rotor 34. The rotor 34 is seen on the shaft 15 and is keyed to the shaft 15 by mating relationship to the flat 16. As will be appreciated, this relationship allows shaft 15 to rotate the rotor 34 and to change lineal axial position through the rotor 34 while not disturbing the rotation or position of the rotor piece 34. The rotor 34 is also formed from a good strength dielectric or insulating material and is provided with a radial recess 37 from which is radially extended a resiliently positioned contactor. Resilience is obtained by a backing spring 38 and the preferred form of the contactor 39 is a cylindrical roller as shown, positioned with its axis perpendicular to the radius forming the axis of the recess 37. The contactor roller 39 is of electrically conductive material, as for example copper, brass, beryllium-copper or the like, selected for good electrical contact and tough or rugged service. Pairs or terminal posts 40 are provided through the barrel 14 of case 12 as by press fit into elongated openings therethrough. These pairs of posts or pins 40 are selectively located in entrapping interference position with the contactor 39. The spacing as between the posts or pins 40 in each pair is such as to detentably entrain the contactor 39 therebetween. The pins or posts 40 are also of electrically conducting material so that through the contactor 39 an electrical circuit is closed when the contactor 39 is in centered position between a selected pair of the pins 40. The axis of each of the pins 40 passes through a radius extended from the axis of the shaft 15 and barrel 14. Closing of an electrical circuit can only occur as bridging of the contactor 39 between adjacent posts or pins 40 occurs. The spacing as between adjacent posts 40 in a selected pair is less than the diameter of the contactor 39. This arrangement with the bias of spring 38 assures excellent detent positioning, proof against chance dislodgment but overcomeable upon manual operation of the shaft 15. By providing a radial recess 41 in the wall 42 of the cylindrical recess 35 a holding neutral position of the switch 11 is very easily provided. This holding neutral position may be defined as a detent "off" position since no pins 40 are provided for integration with selected electrical circuitry. The pins 40, as will be better appreciated, as the description proceeds, provide rivet fastening means to the connector lugs 21, 21a and 21b. The

fasteners 22 pass through the barrel 14 in providing fastening means for the cover 17. The roller contactor 39 accomplishes a line contact with each of the posts 40 in movement so that the roller 39 is assured of rolling wear and excellent contact. As will be appreciated, the post positions may be selected in accord with specific electrical circuits controlled by the switch 11.

In FIGURE 4 the rotor 34 is removed from the case 12 and the reinforcement collet-like bearing projections 43 are shown. These as will be seen project into the cavity 31 of the stem 13 and hug the shaft 15 so as to stabilize the rotor in a true coaxial position on the shaft 15 without interference with lineal movement of the shaft 15 therethrough.

By reference to FIGURE 5 it will be seen that the rotor 34 is sandwiched between the cover plate 17 and the step wall 44 of the barrel 14 and that the bearing projections 43 nest in the stem cavity 33. In addition it will be seen that a shouldering upset 45 is raised radially upward from the flat 16 of the shaft 15 so as to result in interference encounter with the rotor 34 upon one extreme of lineal shaft movement. By reference to the knob 20 the upset 45 integrally provided in the flat 16 of the shaft 15 accomplishes stop engagement when the knob 20 is pulled outward. As will be appreciated, the abutment formed by the upset 45 does not exceed, in extension, the clearance diameter of the stem cavity 31. This is best seen in FIGURES 4 and 5. Hence, the shaft 15 is freely rotatable in the stem 13 and is limited in its axial travel in one direction by interference engagement of the upset 45 with the rotor 34.

In FIGURE 8 the collets 43 are shown in snug slip engagement with the cylindrical shoulders of the shaft 15 and the shaft 15 is shown pulled outward by the knob 20 (FIGURE 1) to the point where the integral upset 45 in the shaft flat 16 abuts the rotor 34.

In FIGURE 7 stoppage of the other extreme of axial shaft movement is seen where the shaft 15 abuts the barrier 30 thus providing a positive stop to push action in the knob 20 or shaft 15. This FIGURE 7 also shows the slight terminal bend 46, in the end of the core 23 of the Bowden wire structure allowing easy assembly of core 23 to shaft 15 by passage of the bend 46 through the barrier opening 32, through the axial opening 28 and into the transverse through opening 29 preliminary to seating the winding 24 in the stem grip 34. When the stem grip 34 is in grip relationship with the winding 24 of the Bowden wire structure, the core 23 is axially fixed and the minute upset bend 46 is adequate to retain the core 23 in excellent interlock in the transverse opening 29 in shaft 15. This accommodates ease of assembly and disassembly only when positive removal of the winding 24 from the stem is accomplished freeing the axial alignment of the core 23 to allow the bend 46 to be threaded out of the coaxial passages 32 and 29.

By reference to FIGURE 6 the contactor 39 is shown in two positions A and B between selected pairs of pins or posts 40. These posts 40 in turn fasten to and are fasteners for the connector pieces 21, 21a and 21b. In position A the contactor closes the schematic electrical circuit 47. In position B, the contactor 39 closes electrical circuit 48. As will be appreciated, this figure is illustrative of only one of many post-contact arrangements, but indicates the switch situation where the center connector 21 is common for two circuits. Other contact arrangements using selected bridging of adjacent contacts to effectuate selected control over specific circuits in electrical or automotive usage is contemplated and will be readily appreciated by those skilled in the art.

By reference to FIGURE 9 the securing of the connectors 21, 21a and 21b using the same pins or posts comprising the posts 40 within the case 12 is clearly shown. This facilitates the conduction of electricity while accomplishing excellent fastening by upset of the ends of the pins 40.

In operation, rotational movement of the shaft 15 is not interfered with by lineal or axial movement thereof and the same is true of lineal movement not interfering with rotational movement and as a matter of fact, both movements may occur simultaneously within the bounds of the stop limits without damage or interruption with desired switch service. The housing 12 is integrally cast as by die casting or otherwise formed from resin material within very close limits at minimum expense. This is also true of the rotor piece 34. The shaft 15 is stock cross section material of good dimensional quality and is simply machined. The Bowden wire units are easily obtained from stock supplies, are terminally crimped and the core wire 23 is easily interlocked to the shaft 15 upon seating of the helix wrapper 24. The posts 40 are pressed or cast in position as desired and the extensions provide simple attaching means for selected connector structure. The switches incorporate integral stops against rotational overrun and lineal overextension in both push and pull directions. The switches 11 are adapted for excellent bearing support upon chassis mounting. The electrical contacting arrangement is very efficient and the detent locating is proof against vibrational maladjustments and switch positioning is by snap or detent action "feel."

25 In automotive service of the most rugged type these switch devices have proved to be easily installed, are trouble-free and amenable to simple disconnect for repair and replacement. The manufacture of the switches thus described is simple and accurate.

30 While the foregoing description expresses the preferred embodiment of the present invention those skilled in the art will readily perceive improvements, modifications and adaptations of the basic device to variant circuit usages and the like. Such improvements, modifications, and adaptations are intended to be included herein limited only by the scope of the hereinafter appended claims.

I claim:

1. A switch comprising: an elongate cylindrical case; a rotor coaxially positioned in said case; a resiliently biased contactor radially extending from said rotor; pairs of contact posts mounted in said case in an interference path for selective contact with said contactor, said contactor selectively closing selected circuits across adjacent of said posts; and a shaft coaxially mounted through said case and said rotor and being keyed to said rotor whereby said shaft is axially reciprocable while providing rotational movement to said rotor.

40 2. The switch combination as set forth in claim 1 wherein said shaft is engageable with stop means provided on said case so as to limit the extent of axial movement of said shaft.

50 3. The switch combination as set forth in claim 1 wherein said shaft includes mounting means for attachment to flexible lineal action devices for remote control.

55 4. In a switch rotor structure admitting of limited lineal movement of the shaft thereof and continuing rotational control over said rotor, the combination comprising: a case; a contactor rotor piece mounted in said case, said case provided with an out-of-round opening axially therethrough; a shaft matingly provided through said out-of-round opening and movable axially through said rotor; and an upset integral extension provided on said shaft; and a stop provided in said case, said stop engageable with said extension upon selected axial movement of said shaft through said rotor piece.

60 5. A switch structure accomplishing detenting rotational selective control and axial lineal movement comprising: an elongate case and an opening axially defined through said case; a rotor in said case; a plurality of pairs of spaced-apart contactor pins located in said case parallel to and radially of the axis of said case and said rotor; a resilient biased contactor radially extending from said rotor into selected bridging contact between selected of said pins; a shaft coaxially mounted through said rotor and said case, said shaft keyed to said rotor and axially

movable in relation to said rotor and said case; and a cover coaxial with said case securing said rotor against lineal displacement and through which said shaft is movable.

6. A switch structure comprising: a case of insulating material defining first and second connected coaxial cylindrical openings; a rotor of insulating material mounted in said first cylindrical opening, said rotor having a resiliently biased contactor radially extending therefrom into contact with said case; plural pairs of spaced-apart 10 contact pins mounted in said case, said contact pins radially arranged in said case and between which said resiliently biased contactor is selectively and detentably locatable upon rotation of said rotor; a shaft coaxially mounted through said rotor and said case, said shaft keyed to said rotor and lineally and axially movable through said rotor; stops means in said case blocking said second opening against unrestricted axial movement of said shaft; a stop abutment on said shaft engageable with said rotor and limiting unrestricted opposite axial move- 15

ment of said shaft; and a mounting cover coaxially provided over one end of said case retaining said rotor against lineal movement and through which said shaft extends.
